UNITED STATES PATENT OFFICE

2,120,915

COTTON CULTIVATOR

William W. Young, Cartersville, Ga.

Application June 5, 1937, Serial No. 146,684

5 Claims. (CL. 97—22)

The present invention relates to improvements in cotton cultivators, and has for an object to provide a cotton chopper in which the chopping or hoeing action will be efficient and positive and in which the expense of manufacture and maintenance of the machine will be relatively small.

Another object of the invention is to provide a simple form of mechanical chopper in which the operative parts are simply and accessibly arranged, and the organization of which lends itself to easy and quick assembly, removal and repair.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view of an improved cotton chopper constructed in accordance with the present invention.

Figure 2 is a rear elevation with parts broken away and parts shown in section.

Figure 3 is a fragmentary perspective view showing a portion of the cylinder.

Figure 4 is a similar view with parts broken away and parts shown in section and showing a portion of the cylinder involving the operative mechanism for the hoes, and

Figure 5 is a perspective view of the inner frame.

Referring more particularly to the drawings, 1 designates the wheels which are mounted to turn freely on a stationary axle 2 extending 35 through the center of the machine, which is in the general form of a cylinder. Such axle 2 is non-rotatively secured to an inner frame 3, which frame is more fully illustrated in Figure 5. There are two wheels 1. Each of these wheels, in the 40 embodiment of the invention shown in the drawings, contains sixteen spokes. The sixteen spokes are spaced around the rim 1 to alternate between eight inches apart and approximately four inches apart, measured on the circumference of the 45 wheels 1. This provides a cylinder divided into sections alternating in size and distributed all around such cylinder. Steel sheets 4 extend from a spoke of one wheel to a corresponding spoke in the opposite wheel 1. These sheets act in the 50 capacity of guards as will be hereinafter explained.

At their inner portions the guards 4 carry tracks 5. These tracks are only in the wider sections of the cylinder. Such tracks 5 serve as 55 runways for the chopper bases or cross-heads 6.

Such cross-head is more particularly shown in Figure 4. Such cross-head may be rectangular in form or of any other shape, the same being wide enough to fit the tracks 5 of adjacent guards 4. The cross-head 6 is mounted to reciprocate in said tracks 5 longitudinally or axially of the cylinder. The cross-head 6 is pulled in one direction by one or more coil springs 7 which are attached to the cross-head 6 at one end and to a fixed block or other part 8 at the other end. The block may also extend between, and be affixed to, the two adjacent guards 4 in each wider section of the cylinder. Such block 8 is preferably in alignment with the cross-head 6. There will be four blocks 8 at one end of the cylinder and four 15 on the opposite end of the cylinder. Preferably the blocks alternate from one end of the cylinder to another in contiguous larger sections of the cylinder.

If desired the coil springs 7 may be secured to 20 the cross-head 6 at the end thereof farthest from the block 8 in order that the extreme length may give more elasticity. The ends of the tracks 5 away from the blocks 8 are left open so that the chopper bases or cross-heads 6 may be removed 25 when necessary.

Each cross-head or chopper base carries hoes 10. Anti-friction rollers 9 are provided whenever necessary on the cross-head 6 for bearing against the tracks 5 or the guards 4, or both, in order to 30 reduce the friction and ease the motion of the cross-heads.

The hoes 10 may be of any form or style and supplied in any appropriate number. In the form of the invention shown, two hoes are shown as 35 carried by each cross-head. These hoes are bolted or otherwise secured to the cross-heads 6. The hoes are curved toward the block 8 in each case as shown in Figure 2. In other words they are curved in the direction of their chopping 40 movement. The hoes may be made adjustable if desired.

Each large section of the cylinder contains one cross-head 6. Four of the cross-heads are connected by their springs 7 to blocks 8 on the left 45 end of the cylinder, and four to blocks 8 on the right end of the cylinder, such blocks alternating. The action of pulling these hoes 10 away from their anchorage and then allowing them to spring back is the principle of operation which creates 50 the chopping action. Cam or spiral tracks 11 are preferably employed for this purpose. The rollers 12 on the cross-heads 6 are adapted to travel over these spiral tracks. There are two such spiral tracks 11. One of these spiral tracks 55

winds in one direction and the other in the relatively opposite direction. One spiral track takes care of four of the cross-heads and the other spiral track operates the four alternate cross-heads. The cam tracks 11 are supported by braces 13 from the non-rotative axle 2. The cam tracks 11 are therefore stationary and do not rotate. The braces 13 are attached to the inner faces of the tracks leaving the outer faces thereof uninterrupted for the passage of the rollers 12 as more particularly seen in Figure 3. These tracks might be said to begin at the brace 13 which points directly downward, curving up and around the axle 2 and gradually coming together about 15 eight inches beyond the last brace 13. The ends of the cam tracks are not necessarily attached together. The tracks do not extend all the way around the circumference of the cylinder but a gap is left between the ends of the cam tracks 20 at the bottom of the cylinder whereby to release the roller 12 and permit the springs 7 to forcibly pull the cross-head 6 and the hoes 10 through the ground. In other words a gap is left between the adjacent ends of each cam track in 25 order that there will be no interference with the roller 12 in the recoil which takes place at this lower point in the cylinder.

The cam tracks 11 before coming together at the origin point will extend some considerable 30 distance beyond the adjacent brace 13. It is also preferred that the cam tracks 11 beyond the brace be made of sufficient thinness to produce comparatively great flexibility in these unsupported ends so that, in the event the machine 35 should be backed while the cylinder is still on the ground, the roller 12 will be free to pass back through and out at this point and be in a position to start forward again. Stops 14 are carried by the guards 4 between the tracks 5 in position 40 to be engaged by the cross-heads 6 whereby to arrest the recoil motion of the cross-heads 6 in a position where the rollers 12 will preferably encounter the origin end of cam track 11.

The narrow sections of the cylinder between 45 adjacent guards 4 serve as a protection for the cotton that must be left to grow. The guards 4 on either side of this four inch space not only protect the cotton from the hoes 10 but keep the dirt from being thrown on it when the chopping action takes place.

The inner frame 3 is a preferably rectangular open frame extending about the cylinder. The ends of the axle 2 are rigidly secured in the side members of the frame in any particular manner, 55 as by the use of bolts or cotter pins 15.

The carriage which supports the cylinder and in which the cylinder is vertically adjustable so as to lower same upon the ground or lift the cylinder up above the ground, consists generally 60 in a rectangular outer frame 16 which is larger than the inner frame 3 and spaced therefrom on all four sides. The outer frame 16 is supported by the ground wheels 17.

Curved brackets 18 on the front part of the 65 outer frame 16 are bolted to upright bars 19 on the inner frame 3, there being a series of perforations in the upright bars 19 for the purpose of vertical adjustment between the two frames. By this adjustment the cross-heads 6 are adjusted 70 to a level position with respect to the ground at the lower side of the cylinder. A hand lever 20 extends upwardly from the front of the right side of the outer frame 16. At the foot of this hand lever are the control gears or locking ratchet 75 21. To this lever 20 is attached a rod 22 running

backwards and connecting with an upstanding arm 25 on a rock shaft 23. The rock shaft is journaled in bearings 24 on the rear bar of the outer frame 16. Arched arms 26 are moved by the rock shaft 23 which extend upward and forward and which hook in the links 27 secured to the inner frame 3 in any appropriate manner, as by staples 28. By swinging the lever 20, the back member of the inside frame 3 can be raised or lowered to the desired height, the front of the inner frame remaining in approximately the same position. When the rear portion of inner frame 3 is lifted, the cylinder will be removed upwardly from the ground.

To the front center of the outer frame is secured the tongue 29 for the purpose of pulling the machine through the field. Carried by the tongue or by the frame 16, or by both, is a seat 31 for the driver and operator. This seat may curve over the cylinder whereby to bring the driver into a 20 convenient position for manipulating the hand lever 20. The spokes 32 of the wheels 1 are attached to hubs 33. The hubs rotate freely about the rounded trunnions 34 of the non-rotative shaft 2 which may be square in cross-section 25 throughout its intermediate length.

In operation, the machine is drawn along by draft animals or by a tractor. The operator occupying the seat 31 may shift the hand lever 20 to lower the drum into contact with the ground. 30 Contact with the ground will cause the drum to roll around. During the course of its rotary movement about the stationary shaft 2, the drum will carry the cross-heads 6 around with it. The rollers 12 on the cross-heads will thus be compelled to travel on the cam tracks 11, such cam tracks being so designed as to move the cross-heads 6 in the tracks 5 away from the stationary blocks 8.

In this manner the springs are stretched or put 40 under a potential condition of tension whereby, when the rollers 12 get to the bottom of the cylinder, that is at the ends of the high points of the cam tracks and move off such high points, the coil springs will exert the energy stored there- 45 in and rapidly draw the cross-heads 6 toward the blocks 8 until the stops 14 are encountered. This recoil movement of the cross-heads 6 occurs when each cross-head is at the bottom of the cylinder where the gaps in the cam tracks occur. 50 This is the position in which the hoes 10 are brought into the ground and into a correct operative position to rake the ground to a proper depth whereby to remove the cotton.

As the cylinder rotates the large sections carrying the cross-heads and the hoes will be presented to the ground alternately with the narrow sections of the cylinder in which no cross-heads or hoes appear. In this way rows of cotton plants will be left to stand while the intervening 60 space therebetween will be plowed up by the hoes 10. This action of the hoes 10 will also cultivate the cotton plants in the rows left by the narrow sections of the drum or cylinder. The walls 4 at the opposite sides of the narrow sections will 65 guard and shield the plants in the manner heretofore described.

The cross-heads 6 alternately act in opposite directions which will have a beneficial effect on the plants and also tend to balance the vibration 70 in the drum incidental to the impact of the cross-heads against the stops 14.

It is obvious that various changes and modifications may be made in the details of construction and design of the above specifically described em- 75

bodiment of this invention without departing from the spirit thereof, such changes and modifications being restricted only by the scope of the following claims.

5. What is claimed is:

1. A cotton chopper comprising a drum adapted to roll along the ground, guard partitions in said drum dividing same into sections, tracks in alternate sections, cross-heads movably mounted on the tracks, chopping means carried by the cross-heads, stationary cam means, projections on the cross-heads engaging said cam means to move the cross-heads along the tracks, said cam means having a gap at the lower part of the drum, and elastic means connected between said cross-heads and the drum for pulling said cross-heads back to initial position when said projections are released from the cam means.

2. A cotton chopper comprising a drum adapted to roll along the ground, guard partitions set substantially radially in the drum and dividing said drum into a number of large and small sections, the large sections alternating with the small sections, said partitions extending out to the periphery of the drum, tracks carried by said guard partitions in the larger sections, cross-heads mounted to reciprocate in said tracks and to move axially of the drum, projections on said cross-heads, a stationary cam track within the drum positioned to be engaged by said projections for moving the cross-heads in one direction, said cam track having a gap at the lower portion of the drum, chopping means carried by the cross-heads, and elastic means for drawing the cross-heads back to initial position when the projections are released by said cam means.

3. A cotton chopper comprising a drum adapted to roll along the ground, chopping means movably carried by said drum and having projections thereon, a cam track in proximity to the drum disposed to engage said projections, said cam track having a gap at the bottom portion of the drum for releasing said projections, means for carrying said cam track, said means being attached to the origin end of the track at a speci-

fied point from its terminal part to render such origin end flexible, and means for drawing said chopping means back to the origin position at the gap in the cam track.

4. A cotton chopper comprising an inner substantially rectangular frame having bearings in the intermediate portions of its side members, a non-rotatable axle having rounded trunnions and end portions fixedly fitted in said bearings of the inner frame, wheels mounted to turn on said trunnions, said wheels having spokes, partitions extending between said spokes, cotton chopping means movably mounted between certain of said partitions, cam tracks carried by said stationary axle, projections on said chopping means engaging said cam tracks for moving the chopping means in one direction, one of said cam tracks extending spirally in one direction and the other spirally in an opposite direction, the projections of every other chopping means engaging one of said cam tracks and the projections of the intervening chopping means engaging the other cam track, said cam tracks having gaps at the lower portions of the chopper, and elastic means for tensioning the chopping means and for restoring same to original position.

5. A cotton chopper comprising a drum adapted to roll along the ground, cotton chopping means carried by said drum, operating means for said cotton means, a shaft for said drum, an inner rectangular frame extending about said drum and supported by the trunnions of said axle, an outer wheeled rectangular carriage extending about said inner frame, means for adjustably and pivotally attaching the forward portion of said inner frame to the forward portion of said carriage, means for connecting the rear portion of the inner frame to the rear portion of said carriage, and including links on said inner frame, and operating means including arched arms engaging said links and a rock shaft connected to said arms for moving said last named means up and down, whereby to raise and lower the frame and drum with respect to said carriage.
